WRAPPING DEVICE

Simon Braude, Paris, France

Application March 30, 1933, Serial No. 663,623
In France March 30, 1932

2 Claims. (Cl. 229—46)

Cartons and all other packing devices for wrapping up light weight articles are generally not sufficient by themselves and must be wrapped with paper and tied with string so that they can be easily carried. It results therefrom that a serious loss of time is caused by the making of parcels.

Some wrapping devices have been proposed which are intended to do away with these drawbacks. However, these wrapping devices are not practical and do not permit of enveloping the object, which has to be introduced into the wrapping device in question through a small aperture. This is very inconvenient when the articles to be packed are soft and not sufficiently rigid for being inserted in that way.

The object of the present invention is to provide a wrapping device which is quite complete in itself, does not necessitate any external means for completely closing it, and can be readily carried by hand.

The wrapping device according to my invention makes it possible to wrap the article with the same facility as if use were made of a mere sheet of paper or of a cardboard box, and it further possesses the rigidity of such a cardboard box. Said wrapping device makes it possible to pack an object of any kind with the greatest facility and rapidity and to close the wrapping device with a minimum loss of time in such a manner that it can then be carried by hand as a parcel tied with string and provided with a handle. Said wrapping device may be manufactured at a very low price, and is, for instance, cheaper than a cardboard box.

The wrapping device according to my invention consists essentially of a sheet of cardboard, paper or any other similar material such for instance as fabric, leather or a paper subjected to a special treatment, cut out in such manner that it can be completely unfolded and subsequently folded so as to be given a shape of a box. Said sheet is further provided with devices which permit to fix it in the closed position through simple and rapid operations. It is further provided with a handle which makes it possible to grasp the wrapping device thus closed, and to carry it easily.

It will be noted that the wrapping device according to my invention comprises no clasp, and necessitates neither gluing nor cutting off and assembling of several parts, and generally no previous fixation. Said wrapping device consists, as above stated, of a single part and therefore avoids the drawbacks of packing devices made of two parts such as a box, one of the parts of

which can be lost, thus making the other useless. On the other hand, the fact of making the wrapping device in a single piece substantially increases its strength, to such a degree that this packing device can readily replace a regular valise, especially when it is made of a sufficiently strong material, such as cardboard. Finally, it can be folded in an ideal manner so that the space it occupies when folded is much smaller than that of unfoldable boxes. It further possesses with respect to such boxes, the advantage of a rigidity equal to that of an unfoldable box. This is due to the fact that, as the corners of the cardboard are not pushed in as in the case of existing foldable boxes, the wrapping device is not deformed whether it is in the folded or unfolded state. Besides, the fact that it is provided with a string and a handle makes it much more practical, and saves a lot of time in wrapping up articles. Finally, the fact that it necessarily comprises a handle, avoids the necessity for the buyers to take the parcel under their arm, thus hiding the advertising inscriptions that may exist on the wrapping.

Preferred embodiments of the present invention will be hereinafter described with reference to the appended drawings given merely by way of example, and in which:

Fig. 1 shows the wrapping device fully unfolded and flattened, said wrapping device being provided with closing means according to another embodiment of my invention;

Fig. 2 is a perspective view of the folded wrapper of Fig. 1.

Figs. 3 and 4 are perspective views similar to Fig. 1 showing several other means of closing the wrapping device.

In the drawings, I have shown at 1—2, a sheet of paper which can be folded along four horizontal lines *a*, *b*, *c*, *d*, shown in dotted lines in Fig. 1, and along two vertical lines *e*, *f*. Bands 3, 4 and 5, located respectively along the outer side of band 1, between bands 1 and 2, and along the outer side of band 2, are preferably reinforced by bands of cardboard or any other suitable material. Band 3 carries a handle 15 and a string or ribbon 14.

Band 5 carries a small disc 16 which is intended to serve for the fastening of ribbon or string 14, when the package is made. Said disc 16 can also be replaced by any other fixation devices.

Each of the bands 17 and 18 has a string, 24 and 26 respectively, attached to it at points adjacent band 1 about midway thereof. The band

2, at its central portion has a disc 27 attached thereto.

When an article has been placed on band 2, it is sufficient to fold up edges 17, 18, 4 and 5 of said band along lines e, f, b, a, and to bring band 1 into a direction parallel with band 2 by folding it along line c. Said band 1 plays a part somewhat similar to that of the cover of a carton. There then remains, in order to completely close 10 the wrapping device, to tie string 14 to disc 16 and loop strings 24 and 26, about disc 27. The wrapping device is now completely closed, and is in the state shown in Fig. 2 in which it can be readily carried by means of a handle 15.

15 It will readily be understood that the wrapping device according to the present invention can be utilized for the packing of any object whatever, the material of which it is made being chosen according to the weight and to the nature 20 of the object to be packed. Said wrapping device may be reinforced in any suitable way, for instance by means of three bands of greater strength 1, 6 and 8, which permit the wrapping device to assume the form of a carton when it is closed, and to fix handle 15 and the fastening devices.

In that way, once it is closed as shown in Fig. 2, the wrapping device has the shape of an ordinary box.

30 In the embodiment of my invention shown in Fig. 3, the closing or fastening of the wrapping device is also effected by means of two strings 28 and 31, the ends of which are fixed to sides 42 and 43 of the box, and the other ends of which are fixed to small discs 29 and 30 fixed at each 35 end of side 2 of the wrapping device.

In the embodiment of Fig. 4, the wrapping device is closed in a manner similar to that of Fig. 3, with the difference that strings 28 and 31 40 carried by the sides of the wrapping device are tied to corresponding strings 32 and 33 replacing discs 29 and 30.

While I have described what I deem to be practical and efficient embodiments of my invention, 45 it should be well understood that I do not wish

to be limited thereto as there might be changes made in the arrangement, disposition and form of the parts without departing from the principle of my invention as comprehended within the scope of the appended claims.

5

What I claim is:

1. A wrapping device of the type described, which comprises, in combination, a single sheet of a suitable material provided with four parallel fold lines so as to divide the sheet into five 10 parallel bands, and with two fold lines at right-angles to the first-mentioned ones, and further provided with slits extending in line with the first-mentioned fold lines and between the second-mentioned fold lines and the corresponding 15 edges of the sheet, so as to form on the outer side of each of said second-mentioned fold lines four rectangular bands independent from one another and each of which is separated from one of the first-mentioned five bands by one of 20 said second-mentioned fold lines, so that the sheet can be folded along said lines directly and without any previous operation in such manner as to form a rigid box, the first and the fifth of the first-mentioned bands overlapping 25 each other and the four second-mentioned bands overlapping one another, so as to form the ends of the box when the sheet is in the folded position, all the elements thus limited by said fold lines and said slits being entirely free and independent from one another, except for their being connected through said fold lines, when the sheet is in the unfolded position, and at least one fastening string fixed to one of the second-mentioned bands, and means on the second of the 30 five first-mentioned bands for fixing the free end of said string to said last-mentioned band.

2. A wrapping device according to claim 1 further including at least one fastening string 40 fixed to the first of the five first-mentioned bands and means on the fifth of said five first-mentioned bands for securing the free end of said last-mentioned string to said fifth band.

SIMON BRAUDE. 45
